(57) **CLAIM**

The ornamental design for a mounting block for a vehicle storage compartment, as shown and described.

DESCRIPTION

FIG. 1 is a top front perspective view of a first embodiment of a mounting block for a vehicle storage compartment; FIG. 2 is a bottom rear perspective view of the mounting block of FIG. 1; FIG. 3 is a first side elevation view of the mounting block of FIG. 1;

FIG. 4 is a front elevation view of the mounting block of FIG. 1;

FIG. 5 is a second side elevation view of the mounting block of FIG. 1;

FIG. 6 is a rear elevation view of the mounting block of FIG. 1;

FIG. 7 is a top plan view of the mounting block of FIG. 1;

FIG. 8 is a bottom plan view of the mounting block of FIG. 1;

FIG. 9 is a top front perspective view of a second embodiment of a mounting block for a vehicle storage compartment;

FIG. 10 is a bottom rear perspective view of the mounting block of FIG. 9;

FIG. 11 is a first side elevation view of the mounting block of FIG. 9;

FIG. 12 is a front elevation view of the mounting block of FIG. 9;

FIG. 13 is a second side elevation view of the mounting block of FIG. 9;

FIG. 14 is a rear elevation view of the mounting block of FIG. 9;

FIG. 15 is a top plan view of the mounting block of FIG. 9; and,

FIG. 16 is a bottom plan view of the mounting block of FIG. 9.

This design is directed to a mounting block for a vehicle storage compartment. Any broken lines show unclaimed subject matter only and form no part of the claimed design.

1 Claim, 16 Drawing Sheets
